UNITED STATES PATENT OFFICE.

WALTER J. DREW, OF GRANDVILLE, ASSIGNOR TO MICHIGAN CARPET SWEEPER MANUFACTURING COMPANY, OF GRAND RAPIDS, MICH.

CARPET-SWEEPER.

SPECIFICATION forming part of Letters Patent No. 229,389, dated June 29, 1880.

Application filed March 29, 1880. (No model.)

To all whom it may concern:

Be it known that I, WALTER J. DREW, of Grandville, in the county of Kent and State of Michigan, have invented certain new and useful Improvements in Carpet-Sweepers; and I do hereby declare that the following is a full, clear, and exact description thereof, reference being had to the accompanying drawings, and to the letters of reference marked thereon, which form part of this specification.

The nature of my invention consists in the construction and arrangement of a carpet-sweeper, as will be hereinafter more fully set forth.

In order to enable others skilled in the art to which my invention appertains to make and use the same, I will now proceed to describe its construction and operation, referring to the annexed drawings, in which—

Figure 1 is a longitudinal vertical section of my invention. Fig. 2 is a cross-section of the same with the brush removed. Fig. 3 is a cross-section, showing the gearing; and Figs. 4, 5, and 6 are detail views.

A represents the box or casing of my carpet-sweeper, having its bottom entirely open. Lengthwise in the center of this box or casing is the revolving brush B, one end of which is placed in a stationary ring, a, while the other end has a journal, b, attached to one end of the casing. On this end of the brush is a friction wheel or roller, C, against the edges of which work two rubber-covered wheels, D D, one on each side, as shown in Fig. 3. Each wheel D has its journal-bearings in a frame, F, which is movable in a stationary frame, E, the journals of the wheel passing into slots e in said stationary frame. These frames E are secured to the end of the casing by screws or any other suitable means in an inclined position, so that the weight of the machine may aid the springs G to keep the wheels at the higher or inner end of the slots, or, in other words, the wheels project slightly below the bottom of the casing, and the weight of said casing will therefore cause the journals of the wheels to slide along the inclined slots to their highest point.

G is a spring placed between the two frames E and F to press the latter inward, so that the

wheel D may be held in contact with the roller C. By this arrangement of springs and gearing the wheels cannot get out of line and twist sidewise, as is liable to be the case when one spring is employed in each side of the wheel. Any pressure on the surface of the wheels causes them to move back in squarely and evenly.

In the ends of casing A, on each side of the brush B, is pivoted a dust-pan, H, the inner edge of which forms the inclined dust-board I. This dust-board is usually made stationary in carpet-sweepers and separate from the revolving pans, and is hence much in the way for cleaning the machine of thread, &c., besides hindering in taking out the brush. These objections are overcome by making the dust-board a part of the working-pan.

At one end the pans H are provided with a slot, x, the slot in one pan being above and the other below the pivot, and in these slots work pins i i, projecting from a sliding plate or lever, J. This plate has also another pin, h, projecting through a horizontal slot, y, in the end of the box or casing A. By this arrangement I get a horizontal movement of the plate J on a line parallel with the bottom of the case, accomplishing the dumping of the pans in a much better and easier manner than where the plate describes a semicircle, as in some sweepers, and making it unnecessary to use a spring or other device to keep the pans in position.

K is a socket for the handle, which is forked at its lower end to receive the arms or bails L extending over the case and journaled in its ends, as seen in Fig. 1.

Upon one of the journals of the bail L is pivoted a segmental plate, R, which has a slot at n to fit over the projecting pin h, and on the bail itself is a pin or lug, m.

When the machine is being pushed over the floor the pans will be held in the proper position by the weight of the machine; but when raised from the floor and the handle elevated the lug m on the bail will strike the plate R and rotate it, and the pin h, being held in the slot n, will be pushed along the slot y, and by this means the plate or lever J is moved and the pans dumped. This may be done at arms' length or out of a door or window, thus pre-

venting the dust from being blown on the person using the machine and rendering it more convenient and handy.

In other machines of this kind the connection between the pans for reversing them act on the principle of a lever, it being pivoted to a certain point on the end of the pan and moves on a circle around the hanging pivot of the pan, so that when closed the leverage is reduced so low that it is difficult to hold the pans in place, and requires a strong spring to do so.

My device acts on the principle of an inclined plane, reversing the power of leverage over the pan.

When the pans are closed the pivots recede from the centers or hanging pivots of the pans, and are at the farthest distance from them, thus giving the most leverage and requiring the least power to hold them firmly closed.

Having thus fully described my invention, what I claim as new, and desire to secure by Letters Patent, is—

1. In a carpet-sweeper, the combination of revolving brush B and inclined stationary

frames E E with sliding frames F F, carrying rollers D D, arranged to gravitate toward each other, substantially as and for the purpose set forth.

2. The combination, in a carpet-sweeper, of pivoted pans H H, sliding connecting-plate J, having pin h, pivoted segmental plate R, having notch n, and the pivoted bail L, with its pin or lug m, all constructed and arranged to operate substantially as and for the purpose set forth.

3. The within-described carpet-sweeper, consisting of case A, revolving brush B, friction-roller C, wheels D D, stationary frame F F, inclined frames E E, bail L, segmental plate R, and plate J, all constructed and arranged to operate as set forth.

In testimony that I claim the foregoing as my own I affix my signature in presence of two witnesses.

WALTER J. DREW.
